UNITED STATES PATENT OFFICE.

FREDERICK C. OVERBURY, OF HILLSDALE, NEW JERSEY, ASSIGNOR TO THE FLINTKOTE COMPANY, OF BOSTON, MASSACHUSETTS, A CORPORATION OF MASSACHUSETTS.

METHOD AND MEANS FOR MAKING PREPARED ROOFING ELEMENTS.

1,314,477.

Specification of Letters Patent.

Patented Aug. 26, 1919.

Application filed December 28, 1917. Serial No. 209,229.

To all whom it may concern:

Be it known that I, FREDERICK C. OVERBURY, a citizen of the United States, residing at Hillsdale, in the county of Bergen and 5 State of New Jersey, have invented new and useful Improvements in Methods and Means for Making Prepared Roofing Elements, of which the following is a specification.

This invention has relation to the manufacture of prepared roofing in the form of "shingle strips", so-called, which consist of slabs or strips having spaced tabs or projections, which are exposed when the strips are laid in overlapping rows, and present 10 the appearance of shingles, tiles or slates. Such prepared roofing consists of a foundation sheet of fibrous material, usually rag felt, which is porous and absorbent, and which is saturated or impregnated with a 15 relatively low melting-point asphalt or other hydrocarbon to make the sheet waterproof, and coated with a layer of a relatively high-melting-point pitch or asphalt, in which is partially embedded a surfacing 20 material such as crushed tile, slate, granite, or other form of grit to give the roofing an ornamental appearance in addition to increasing its capacity to withstand the action 25 of the elements and increasing its fireproof 30 and acidproof qualities.

Heretofore it has been the practice first to produce a sheet of roofing such as described, and then to form it into shingle strips by means of cutting machines by 35 which transverse slots are cut in the sheet, and the sheet is slit longitudinally as described in my Patent No. 908,125 or by which the sheet is severed transversely into shingle strips as described in my Patent No. 40 1,182,416. While such a method of producing shingle strips has been commercially successful, yet certain difficulties have presented themselves which militate against an economical and rapid production of the 45 strips.

Saturated, coated and mineral-faced roofing is difficult to cut easily, because the grit wears out the knives very rapidly, especially those which are employed for cutting 50 the slots in the sheet, and because of the character of the saturating and coating compounds, they tend to clog the dies or cutters especially when mixed with the grit. Moreover the waste pieces, which are cut

from the sheet in forming the slots therein, 55 cannot easily be utilized because of the embedment therein of the crushed mineral or grit.

The present invention has for its object to remedy and overcome the faults and difficulties which have heretofore inured to the method of manufacture hereinbefore briefly described. This is accomplished, briefly speaking, by forming the slots in the sheet before it is coated and surfaced, and then 60 after the sheet has been coated and surfaced cutting it into strips. In this way, the slotting is accomplished without permitting the knives to come into contact with the grit, and the waste pieces may be treated to reclaim the 65 saturating compounds and the felt without having any grit admixed therewith. A further beneficial result is secured in that the coating covers the cut edges or walls of the slots and increases to some extent the 70 thickness thereof, and enables the walls of the slots to be surfaced with the grit, whereby the exposed portions of the strip 75 appear to be relatively thicker and more massive. 80

On the accompanying drawing,—

Figure 1 represents, conventionally, apparatus for the practice of my invention.

Fig. 2 illustrates the sheet during the course of its manufacture into shingle 85 strips.

Fig. 3 represents a section on the line 3—3 of Fig. 2 on a larger scale.

So far as the details of manufacture are concerned, it is quite immaterial whether 90 the resultant shingle strips are cut crosswise of the sheet, as illustrated in my Patent No. 1,150,298, dated August 17, 1915, or whether they are cut lengthwise of the sheet as shown in my said Patent No. 908,125. In 95 either case, the slotting is accomplished before the coating compound and the surfacing grit are applied to the sheet. On the drawing I have shown the instrumentalities for forming the cross-cut shingle 100 strips, but I do not thereby intend to exclude the use of instrumentalities for forming the length-cut strips.

The sheet of felt or other equivalent porous, absorbent, fibrous material is shown 105 as being drawn from a roll 10, whence it is passed through the saturation vat 11 in which is contained molten low-melting-

point asphalt or other suitable hydrocarbon compound, kept in liquid condition by any suitable heating means such as steam coils 12. After passing through the squeeze rolls 13, by which all of the excess saturating compounds is removed from the sheet, leaving it comparatively dry, the sheet is passed around drums 14 which are supplied with a cooling or refrigerating medium for chilling 10 the sheet and setting the compound. Preferably the sheet is chilled to a temperature at which the saturating compound is relatively hard. From the chilling rolls the sheet is now conducted to a slotting machine indicated as a whole at 15, and which comprises feed rolls 16, and slotting rolls 17, 18. This machine may be with convenience constructed substantially as shown and described in the patent to Gerry G. 20 Gardner, No. 1,191,297, dated July 18, 1916, to permit the escape of the waste pieces (formed by the dies in cutting the slots) from the lower roll, in which event it will be also provided with knives for slitting 25 the sheet lengthwise through the slots. As shown, however, the roll 17 has a plurality of dies or cutters for coöperation with recesses in the roll 18 to cut a transverse row of longitudinal slots in the sheet at intervals 30 along the length thereof, and the waste pieces delivered from the lower roll are delivered by a chute 19 to a basket or receptacle 20. In Fig. 2 the raw felt sheet is indicated at *a*, and the saturated portion 35 is indicated at *b*. The longitudinal slots therein are indicated at *c*. The number of the slots will vary in accordance with the width of the sheet, and the length and width and spacing of the tabs or projections 40 on the finished shingle strip. For example, the slots intermediate the edges of the sheet may be one-half inch in width and nine inches in length and spaced laterally apart six inches, and the slots in the edges may 45 be one-quarter inch. Of course these proportions are varied according to circumstances, and the slots are spaced longitudinally of the sheet according to the desired width of the several shingle strips. 50 After leaving the slotting machine, the saturated and slotted sheet is now coated with a weatherproof compound of high-melting-point pitch or asphalt by passing it between carefully adjusted rolls 21, 22, 55 which preferably are steam-heated. The molten pitch or asphalt is delivered upon the sheet by a spout 23 at a point close to the nip of the rolls, the sheet passing over a stationary table or plate 124 to prevent 60 the pitch from pouring through the slots. Any pitch or asphalt which escapes through the slots in the lower roll as the sheet is fed through the rolls may be scraped therefrom by a scraper 24 and delivered 65 to a tank 25 for re-use. The scraper

24 and the tank 25 may both be steam-heated, if desired. In Fig. 2, the coated portion of the sheet is indicated at *d*.

While the coating is in a plastic condition, the sheet is passed beneath a hopper 70 26 containing crushed or flaked slate, tile, brick, granite, or other mineral, and a thin stream of the grit is deposited upon the coating. The grit which falls through the slots is deflected by a chute 27 into a receptacle 28 for re-use. The sheet is now carried over a roll 29 and under rolls 30, 31, so that the excess grit may be discharged or be dropped from the sheet into a receptacle 32 for re-use, and is then passed between pressure rolls 33, 33, for partially embedding the grit in the coating. The various rolls are all synchronized as to peripheral speed so that the sheet is fed uniformly from the roll of felt 10 to the pressure rolls 33, 33. After the grit has been embedded in the plastic coating, it is desirable that the sheet should be cooled to permit the coating to harden and set before it is severed into shingle strips. Any suitable cooling means may be employed for this purpose, but I have illustrated conventionally at 34 a festooning mechanism for this purpose. From this mechanism the sheet is delivered to the strip-cutting machine which is provided with feed rolls 35, and cutters comprising a stationary shear blade 36 and an associated chopping blade 37. The chopper 37 is rotated at such a rate of speed in relation to the speed of travel of the sheet, that the sheet is severed on straight transverse lines *e*—*e* and *f*—*f*, the cut *e*—*e* being midway between the ends of each row of slots, and the cut *f*—*f* being midway between two adjacent rows of slots. 95 As a result of the slotting and the transverse severance of the end of the sheet, there are rapidly produced duplicate shingle strips, each having one straight longitudinal edge, and on the other edge a plurality of spaced tabs or projections, which, when the strips are laid in overlapping relation on a roof, present the appearance of shingles or tiles. 100

In Fig. 3 I have shown on a larger scale a section through one of the shingle strips on the line 3—3 of Fig. 2, for illustrating, in conventional and exaggerated form, the result accomplished by slotting the sheet before the coating and mineral surfacing materials are applied. The coating compound covers the walls of the slots as at *g* and generally extends beyond the walls on the under side of the sheet as indicated at *h*. This gives additional waterproof protection to the cut edges, and increases the 115 thickness of the sheet adjacent the said edges. Moreover the mineral material adheres to the compound *g* as conveniently illustrated.

By the practice of the process as herein

described, I am able to effect a saving in the coating compound and the grit in the production of the roofing. I make it possible to reclaim the saturating compound in 5 the waste cuttings and greatly increase the length of life of the slotting cutters.

I have already indicated that the slots may be formed in different ways in the sheet, but I refer thereto once more to point 10 out that the particular arrangement of the slots is immaterial so long as they are so formed that, when the sheet is eventually severed, each shingle strip has a plurality of spaced tabs or projections.

15 What I claim is:

1. A method of making shingle strips, which consists in saturating a sheet of felt with a hydrocarbon compound, then forming slots in said saturated sheet, then applying the plastic coating upon the slotted sheet, and severing said sheet in lines transverse to the slots to form shingle strips.

2. A method of making shingle strips, which consists in saturating a sheet of felt 25 with a hydrocarbon compound, forming slots in the saturated sheet, applying a plastic coating to said slotted sheet, applying a layer of grit to the coated sheet, and severing the sheet into shingle strips of pre- 30 determined lengths and widths, each having a plurality of tabs or projections.

3. A method of making shingle strips, which consists in forming transverse rows 35 of longitudinal slots in said sheet, coating the slotted sheet with an asphaltic plastic compound, embedding grit in the asphaltic

coating, and severing the sheet transversely of the slots into shingle strips of predetermined length and width.

4. In combination, the following instru- 40 mentalities, to wit: means for saturating a sheet of felt with a water-proofing compound, means for forming slots in said saturated sheet, means for applying a plastic coating on said slotted sheet, and means for 45 severing said sheet in lines transverse to said slots to form shingle strips.

5. In combination, the following instru- 50 mentalities, to wit: means for saturating a sheet of felt with a water-proofing compound, means for forming slots in said saturated sheet, means for applying a plastic coating on said slotted sheet, means for applying a layer of grit to the coating on said sheet, and means for severing said sheet in 55 lines transverse to said slots to form shingle strips each having a plurality of tabs or projections.

6. In combination, the following instru- 60 mentalities, to wit: means for successively forming transverse rows of longitudinal slots in a sheet of roofing material, means for coating said slotted sheet with a plastic asphaltic compound, means for applying a layer of grit to said coated sheet, and means 65 for severing said sheets transversely of said slots into shingle strips of predetermined length and width.

In testimony whereof I have affixed my signature.

FREDERICK C. OVERBURY.
